UNITED STATES PATENT OFFICE.

FRANCIS J. McCORMICK, JR., AND FRANCIS J. McCORMICK, OF DAYTON, OHIO.

DESIGN FOR A WATER-CLOSET BOWL.

SPECIFICATION forming part of Design No. 28,545, dated May 3, 1898.

Application filed December 1, 1897. Serial No. 660,444. Term of patent 14 years.

To all whom it may concern:

Be it known that we, FRANCIS J. McCORMICK, Jr., and FRANCIS J. McCORMICK, citizens of the United States, residing at Dayton, in the county of Montgomery and State of Ohio, have invented and produced a new and original Design for a Water-Closet Bowl; and we do declare the following to be a full, clear, and exact description of the same, reference being had to the accompanying drawings, forming a part thereof.

Figure 1 is a perspective view of a water-closet bowl, showing our design. Fig. 2 is a mid-sectional view of the same.

The leading or material features of our design consist in the form or contour of the seat or upper portion of the bowl, so that it stands high above the wall of said bowl, and in extending it horizontally on both sides of said wall substantially equidistant, the wall and seat being one and inseparable parts A and B, respectively. The seat B is projected in a uniform curve equal distances inwardly and

outwardly from the point of the intersection of the wall therewith, so that the said wall occupies a central position with relation to the seat. The seat or upper portion B joins the wall A on the outside in a curve, while on the inner side it projects inwardly in a horizontal line and forms an annular shoulder C at the point where it joins said wall and above and beyond which the inner edge of said seat B projects.

Having fully described our invention, what we claim, and desire to secure by Letters Patent, is—

The design for a water-closet bowl substantially as herein shown and described.

In testimony whereof we affix our signatures in presence of two witnesses.

FRANCIS J. McCORMICK, JR.
